UNITED STATES PATENT OFFICE.

GEORGE H. TAGGART, OF NEW YORK, N. Y.

AUTOMATIC STOP FOR PHONOGRAHS.

1,327,501.

Specification of Letters Patent.

Patented Jan. 6, 1920.

Application filed September 3, 1918. Serial No. 252,404.

To all whom it may concern:

Be it known that I, GEORGE H. TAGGART, a citizen of the United States, and a resident of the city of New York, borough of Manhattan, in the county and State of New York, have invented a new and Improved Automatic Stop for Phonographs, of which the following is a full, clear, and exact description.

10 This invention relates to automatic stops for phonographs of the general type covered by Letters Patent of the United States No. 1,286,833, issued to me on the 3rd day of December, 1918, the purpose in both inventions being to provide a tripping mechanism for the brake whereby the brake will act automatically upon the turntable, stopping the rotation thereof at the moment that the stylus reaches the inner end of the record groove, or immediately thereafter.

15 Among the objects of the present improvement is to simplify and cheapen the construction of means for accomplishing the above object, all as will be more fully set forth and described with reference to the accompanying drawings of which—

20 Figure 1 is a plan view of my improvement on the top of a phonograph case and with the reproducer and turntable indicated in broken lines.

Fig. 2 is a vertical sectional view on the line 2—2 of Fig. 1.

Fig. 3 is a plan view of a portion of Fig. 1 showing the parts in tripped position.

25 Fig. 4 is an enlarged detail view of the trip mechanism, the normal running position being shown in full lines, and the preliminary tripping position being in dotted lines.

30 Fig. 5 is an enlarged vertical section on the line 5—5 of Fig. 1.

Fig. 6 is a detail view of the means for securing the base plate of my improvement to the deck of the casing.

35 Fig. 7 is an enlarged detail view of a modification; and

Fig. 8 is a horizontal detail view on the line 8—8 of Fig. 5.

40 Referring now more particularly to the drawings, I show at 10 the top or deck of the main portion of a phonograph case in which is formed a hole or depression 11 in the center of which is the motor driven turntable post 12 on which the turntable 13 is supported as usual for the accommodation of the record disk 14. At one side of or at

the rear of the turntable is the oscillating tone arm 15 coöperating in any well known manner with a thimble 16 having a smooth topped flange 17 connected to the deck and through which communication is had with the horn or sound amplifier, not shown. Obviously I do not wish to be limited in practice to any unnecessary features of construction, and for the most part the devices thus far described are conventional, the operation of which is well understood.

45 The brake comprises a shoe 18 pivoted at 19 to an arm 20 pivoted at 21 on a metal plate 22 adapted to be readily secured to the deck 10 as by means of screws 23 projected through large holes 24 for the sake of accuracy of adjustment. (See Fig. 6.) Sheet metal is well adapted for this structure because of its relatively cheap nature and ready adaptability in practice. 50 25 indicates a corner portion of the base plate 22 bent down at 26 so as to project into the pit 11 reaching nearly to the post 12, wherein is journaled a wheel 27 on a vertical fixed pivot 28. This wheel 27 is in constant frictional contact with the post 12 from which it is rotated as indicated by the arrows while the turntable is rotating. Extending upwardly from the wheel 27 is a 55 stud 29 which describes a small circle concentric with the pivot 28. The relative diameters of the post 12 and wheel 27 may vary somewhat, but as shown the wheel is larger and hence makes fewer rotations than 60 the turntable. A spring 30 fixed at one end to the arm 20 and anchored at 31 tends to draw the brake shoe against the periphery of the turntable. The shoe, however, in running position is held out of contact with the 65 turntable by means of a trip lever 32 mounted on a fixed pivot 33 on the base 22 and having coöperation with the end of the arm 20 remote from its pivot 21 preferably through an anti-friction roller 34 seated in 70 an angular shaped seat 35. The outer end of the trip lever constitutes a finger piece 36 whereby the brake may be either set or released at any time by hand. The seat 35 in the form indicated serves two direct functions. The wing thereof that projects radially constitutes a stop limiting the movement of the roller 34 in a direction away from the brake shoe when releasing the 75 80 85 90 95 100 105 110 115 120 125 130 which extends substantially circumferential with respect to the turntable constitutes the normal holder for the brake shoe, resisting the force of the spring 30. The active portion of this wing, however, passes but slightly beyond the line of centers of the roller 34 and pivot 33 so that a very slight movement or force applied to the trip lever toward the brake shoe suffices to trip the 10 brake to the position shown in Fig. 3, the roller rolling easily around the circumferential wing of the seat 35.

Surrounding the thimble 16 and supported above the flange 17 thereof is a flat 15 ring 37 having a notch 38, the same being indicated as being formed in the inner edge thereof adjacent to the front side of the thimble and into which a finger 39 carried by the tone arm 15 projects loosely. Hence 20 with the oscillation of the tone arm in playing direction the ring 37 is given a corresponding partial rotation around the vertical axis of the tone arm. Loosely supported upon or above the flat ring 37 is another ring 40 loosely surrounding the 25 thimble 16 and having a long cutaway or notch 41 so as to always clear the tone arm and the finger carried thereby. Extending forward from the ring 40 is an actuator arm 30 42 extending toward the pit 11 and over the base plate 22. This actuator arm 42 is held in horizontal position by means of a counterbalance 43 on the opposite side of the thimble. A washer 44 of leather, or its 35 equivalent, applied between the rings 37 and 40 suffices to cause the ring 40 and actuator arm to rotate with the ring 37 and yet permitting relative slippage between the two rings when desired as will presently 40 appear.

The trigger mechanism comprises an arm 45 loosely pivoted at 46 to a trigger lever 47 having fixed pivot connection to the base 48 and to the opposite end of which is fixed a 45 tensile spring 49 anchored at 50. The normal tendency of this spring is to hold the outer end of the arm 45 in rolling contact with the otherwise free end of the actuator arm 42. This arm 45 with respect to the 50 pivot 46 constitutes a lever of the first class, one arm of which, namely between the pivot 46 and the end of the actuator arm, is relatively very short, while the other arm is relatively long and has secured to its end at 55 the pivot 51 the trigger arm 52. A spring 53 connected to the outer end of the trigger arm 52 and to the intermediate portion of the arm 45 tends to hold the trigger arm in the position shown in Figs. 1 and 4, with a 60 lug 54 carried by the trigger arm bearing against the arm 45. The extent of oscillation of the arm 45 is limited by stops 55 on opposite sides thereof.

The trigger arm 52 when made of sheet 65 metal comprises a downwardly projecting

end flange 52^a and a similar side flange 52^b between which there is a gap 52^c. These parts are so designed that when the machine is running normally the stud 29 approaching the trigger arm passes through the gap 70 52^c beneath the top or main portion of the arm and strikes against the inner surface of the end wall or flange 52^a, whereby the trigger arm and parts connected thereto before the roller 27 makes a half turn will be 75 moved from the full line position of Fig. 4 to the dotted line position thereof. By this movement of the trigger mechanism toward the left the flange 52^b is brought into the path of the stud 29. 80

In the practice of this invention it will be understood that the tone arm has a practically constant and uniform progression toward the center of the turntable, the stylus being positively fed toward the center of 85 the disk by virtue of the spirality of the record groove. Hence, while the wheel 27 is making a one half turn, or before the stud 29 thereof will have moved from its dotted line position to the full line position in Fig. 90 4, the turntable will have made at least one whole rotation and the stylus will be fed toward the center of the disk to a distance at least equal to the width of a thread. Thus the tone arm will be moved positively toward the left and the ring 37 will be positively moved in the same direction through a similar angle. The upper ring 40 and actuator arm 42 will be moved in a similar direction by friction through the washer 44 100 and thereby the arm 45 will be oscillated in the opposite direction around the pivot 46 as indicated by the arrows on Fig. 1 and the trigger arm 52 will be returned consequently to its normal position as shown in 105 full lines in Fig. 4 prior to the next approach of the stud. Thus the actuator arm will be given continual oscillations of short amplitude at each rotation of the wheel 27, and the arm 45 will be given the same number of oscillations carrying with it the trigger arm 52 with larger amplitude. This action continues without actuation of the 110 brake so long as the tone arm and stylus are moved toward the center of the disk. When, however, the stylus reaches the inner end of the spiral record groove where the groove merges into a circle concentric with the post 12 the tone arm is held thereby from further oscillation. Consequently when the 115 stud 29 again engages the inner surface of the end flange 52^a and draws the trigger mechanism to the left, the dotted line position of Fig. 4, the parts will remain in this position since the actuator arm 42 is no 120 longer functional to restore them to normal position. Thus when the wheel 27 makes another partial rotation the stud 29 strikes the flange 52^b and swings the trigger arm in a clockwise direction around its pivot 51 as 125 130

shown in Fig. 3, the opposite or outer end thereof acting to swing the trip lever 32 setting the brake. As soon as the stud 29 passes the flange 52^b the spring 53 returns 5 the trigger arm to its normal position.

The engagement contact between the actuator arm 42 and the shorter arm of the lever 45 is or may be mainly that of rolling friction, for although I indicate in Figs. 1 and 3 10 toothed engagement so as to prevent lateral displacement of one member with respect to the other, I indicate in the detail view of Fig. 7 the essential nature of this contact wherein the end of the arm 42 has rolling contact only on the rounded end of the arm 45.

In order to prevent the possibility of premature setting of the brake as for instance during the operation of placing the stylus 20 upon the record disk, and at which time the tone arm may be held for a brief period in a stationary position, I provide some means acting automatically upon the actuator arm 42 keeping it in an advanced position. The 25 means I have found suitable for this purpose comprises a spring 56 pivoted at 57 and having two arms, one arm having a finger 58 bearing against the rear edge of the arm 42, while the opposite arm bears against the 30 edge of the ring 37. This ring is provided with a depression 37' so located and long enough to accommodate the adjacent end of the spring 56 during the normal playing and 35 stopping operation above described, but when the reproducer is held at or near the edge of the disk the spring lies upon the unnotched portion of the ring 37 thereby putting the finger end of the spring under the desired tension for the purpose indicated. 40 With respect to the construction and function of the actuator arm 42 it is to be observed that this arm is always so held at or toward its forward position, either by reason of the spring just mentioned or the frictional driving connection from the tone arm, 45 as to insure that the trigger arm 52 tends to remain out of the path of the stud 29. Hence any vibration of the machine such as 50 may be incident to the winding of the motor, tilting, or jostling of the cabinet, while the record is being played, will not disturb the automatic mechanism and cause the premature setting of the brake.

I claim:

55 1. The combination with an automatic brake for a phonograph turntable, of means to initiate the setting of the brake automatically when the end of the record is reached, said means including a trigger arm, an arm 60 to which the trigger arm is pivotally connected, means to hold the trigger arm normally substantially at right angles to the arm but permitting it to be swung around its pivot to a different angle, means to reciprocate the trigger arm in opposite directions in

alternation continually while the record is being played, the means acting upon the trigger arm to reciprocate it in one direction serving to cause the swinging thereof as aforesaid after the end of the record is 70 reached, and a trip member acted upon by the angular swing of the trigger arm to release the brake.

2. The combination with a turntable, a power member to rotate it, and an automatically operated brake tending when released to stop the rotation of the turntable, of 75 brake controlling means located between the brake and the turntable rotating member to automatically initiate the setting of the 80 brake when the end of the spiral record groove is reached, said brake controlling means including a trip lever acting directly to hold the brake released but pivoted to swing in an arc of a circle, a trigger arm, 85 means supporting the trigger arm for continual reciprocations in opposite directions while the record is being played and permitting the swinging thereof after the record is ended, said trigger arm coöperating with 90 the trip lever to set the brake when the trigger arm swings on its pivot, a member co-operating with the trigger arm to cause reciprocation thereof in one direction and also rotation thereof, and means actuated by the 95 turntable driving means to cause said last mentioned member to move through a circular path.

3. In automatic stop devices for phonographs, the combination with a tone arm, 100 means to cause the tone arm to oscillate in arcs of a circle, and a brake, of means to automatically initiate the setting of the brake when the tone arm ceases to oscillate, said last mentioned means including an annular 105 notched member loosely surrounding the base of the tone arm, an actuator device extending laterally therefrom, and means acting between the tone arm and the annular member tending to hold the actuator mem- 110 ber advanced in the direction in which the tone arm oscillates, said holding means comprising a ring parallel to the annular member, friction means between the annular member and the ring, and a rigid finger carried by the base of the tone arm and projecting loosely into the annular member notch and engaging and positively moving the ring and also the annular member by virtue of said friction means.

4. In automatic stop devices for phonographs, the combination with a tone arm, means to cause the tone arm to oscillate in arcs of a circle, and a brake, of means to automatically initiate the setting of the 125 brake when the tone arm ceases to oscillate, said last mentioned means including an annular member loosely surrounding the tone arm in a horizontal plane and having a long notch along its inner edge, an actuator mem- 130

ber constituting a rigid lateral extension from the annular member, a second annular member in vertical alinement with the aforesaid annular member, and having a notch 5 registering with but shorter than the aforesaid notch, frictional connections between the two annular members, and a finger carried by the base of the tone arm and projecting into both notches aforesaid to 10 cause the oscillation of the annular members with the oscillations of the tone arm and thereby causing the movement of the actuator member through the frictional connections in a corresponding direction.

15 5. In an automatic stop for phonographs, the combination with a tone arm and a brake, of means to automatically set the brake when the tone arm is no longer caused to move toward the end of the record, said last 20 mentioned means including a trip lever, a trigger arm adapted to actuate the trip lever to release the brake, an arm having a rounded end and to whose other end said trigger arm is pivoted, an actuator arm 25 substantially in alinement with the aforesaid rounded ended arm and having rolling con-

tact with the rounded end thereof, said actuator arm being moved in connection with the movement of the tone arm, and means connected to the rounded ended arm to maintain the same pressed with its rounded rolling end against the adjacent end of the actuator arm, and last mentioned means including a trigger lever and a spring acting thereon substantially as set forth. 30 35

6. In trigger means for automatic stops for phonographs, the combination of an actuator arm and another arm having end to end abutting rolling contact, a trigger lever pivoted to said other arm at the center of 40 its rounded end having engagement with the actuator arm, a spring acting upon the trigger lever serving to maintain a uniform frictional contact between the abutting ends aforesaid, a brake trip lever, and means co- 45 operating with the end of said other arm aforesaid remote from its abutting end co-operating with the trip lever to cause the setting of the brake when the end of the record is reached.

GEO. H. TAGGART.
